UNITED STATES PATENT OFFICE.

FREDERIC DE MARE, OF BRUSSELS, BELGIUM.

OZONE-VENTILATOR.

No. 820,656.

Specification of Letters Patent.

Patented May 15, 1906.

Application filed September 23, 1904, Serial No. 225,647.

To all whom it may concern:

Be it known that I, FREDERIC DE MARE, a subject of the King of Belgium, residing at Brussels, in the Kingdom of Belgium, have 5 invented certain new and useful Improvements in Ozone Fans or Ventilators, of which the following is a specification.

My invention relates to fans or centrifugal ventilators which are so constructed and arranged whereby the gas, air, or vapor are electrified at the same time that they are forced or drawn through the apparatus, and more especially to those designed to electrify air and transform a portion of the oxygen into ozone.

The object of my present invention is to produce the electrization of the air, gases, or vapors in the inner part of a body of air or gas, and is arranged in such a manner that 10 the apparatus itself sucks in the gases to be electrified and delivers them after they have been electrified into the same body of gas, air, or vapor.

My invention is essentially distinguished 15 from those already known and used by the fact that the device itself sucks in the gas to be electrified, while in the previous apparatus the gas is furnished to the devices by a separated compressor. It is therefore essential 20 not to confound this device with the apparatuses wherein the electrodes are movable without having another action on the gases than that of electrification, while the present device sucks in, electrifies, and delivers the gas to be treated in a single operation 25 and in the same apparatus. Even if the gas to be treated is fed under pressure it still differs from the known devices in that the compressed gas entering the device serves by 30 its expansion to move the electrified members, while in the known devices the compressed gas entering the electrifying devices has no motive action on the movable electrifying members. The first arrangement of 35 apparatus may be considered as a ventilator and the second as a turbine, and both are adapted, owing to a convenient arrangement of the blades, to electrify the gas which moves alongside the wings.

40 The invention consists of novel structural features and relative arrangements thereof, which will be more fully described hereinafter and then pointed out in the appended claims.

45 A practical embodiment of the invention is represented in the accompanying three sheets of drawings, forming a part of this

specification, in which similar reference characters indicate corresponding parts in all the views.

Figure 1 is a side elevation of the apparatus. Fig. 2 is a vertical section on line 2 2 of Fig. 3. Fig. 3 is a vertical section on line 3 3 of Fig. 4. Fig. 4 is a horizontal section on line 4 4 of Fig. 3, and Fig. 5 is a diagrammatic view showing the manner of connecting up 60 the electrical connection with the apparatus and mode of operating the same.

My device comprises a casing, of porcelain, glass, or any other suitable insulating material, having the usual form of the shells of centrifugal fans or ventilators. This casing is preferably formed or divided in two parts by means of two sections C D, which are separated in the center by a plane perpendicular to the axis of the machine. The sections C 70 D are fixed together by any suitable means passing through bolt-holes H. Separating and interposed between the two sections is a fine glass diaphragm I, of glass, mica, or other suitable dielectric, which, it will be seen, consequently divides the casing of the fan or ventilator in two equal chambers. In this envelop may rotate a movable winged shaft, which consists of an insulating-hub J of any suitable material—such as fiber, ebonite, 80 steatite, porcelain, &c.—and is provided at each end with metal sockets K K', connected with the steel shafts T T' by screws x. (See Fig. 3.) This hub J is rotatable by means of being supported in lubricating-bearings L L', 85 fixed on each side of the casing at the openings of the fan or ventilator. The bearings L L' are fixed to the casing by means of rings M M and two small bosses N N' on the casing, which are adapted to engage with two 90 notches in the rings M, thereby maintaining the bearings in their applied position. On the metal sockets K K', inclosing the insulating-hub J, are fixed straight or curved wings 95 R R, of metal, preferably aluminium, and connected to each other by means of an annular plate or crown S. On the diaphragm I there are two series of wings R R, one on each of its sides. The two sets of wings R R are nevertheless fixed according to the circumference of the hub, one being on the extension of the other axis, as if there were no diaphragm.

At the point where the shaft pierces the diaphragm I there is provided an opening or hole 110 O, slightly larger in diameter than that of the insulating-shaft J. Two insulating-rings P

P', integral with the shaft, prevent discharges in the form of sparks between the wings R R. For this same reason the wings are C-shaped, as shown at Q, and have for their object to facilitate the entrance of the gases from the admission of the ventilator to the interior of the same to be acted upon by the wings R R. Holes V V are provided in the foot-pieces of the half-sections of the casing to secure the apparatus on a suitable base.

From the foregoing description it will be seen that the ventilator or fan is composed of a casing which is non-conducting and the wings or fans of which are in duplicate. The axis of the apparatus is insulated and is provided with two metal sockets which are insulated from each other, each carrying a series of wings, and the casing of the fan or ventilator is divided centrally into two equal chambers by means of a vertical dielectrical diaphragm.

Referring to Fig. 5, 1 is a low-voltage source of electrical energy. 2 is an interrupter. 3 is a high-voltage transformer; 4, the electrifying ventilator or fan; 5, the motor actuating the wings of the ventilator or fan, and 6 is the source of electricity-supply for actuating the motor. If the shaft 5 is rotated more or less rapidly, the system constitutes an ordinary ventilator or fan; but if each of the bearings T T' is connected by means of the terminals U U' to the poles of an electric generator of high pressure and frequency, as indicated in Fig. 5, a disruptive discharge will be produced in the form of an emanation between the edges of each wing and the opposed edge on the same generator, as shown by small dashes a a in Fig. 5. Briefly stated, the apparatus is an electrifier and pump for the gas it electrifies. If instead of leaving the admissions open to the free air they are connected to the conduits, the gas or vapor to be electrified may be sent through the ventilator instead of air, and the gas or vapor may be collected at the mouth end of the ventilator and utilized according to the requirements. As the electric action is a more efficacious one when cold, the insulating-casing may have a double wall with a refrigerating fluid circulating beneath it, which may be varied according to the speed and to the electric energy supplied.

I do not care to limit myself in having the wings integral with the same axis. They may be made independent and turn in opposite directions relatively to each other. In this case the curve of the wings or blades is contrary to those turning in the opposed direction. I may also dispose a number of series of wings separated by means of several diaphragms, each series being electrified in an opposed sense to the next adjacent one.

Instead of having the ventilator driven by a motor I may also compress the gas and utilize its expansion to drive the wings of the

ventilator by reaction, in which case the ventilator would act as a turbine.

As the gases by expanding are cooled they are in as favorable a condition as possible for the electrization. It is important here also not to confound this arrangement, which, if it uses a gas under pressure instead of sucking it in and delivering it as in the first-described case, is very different from the apparatuses into which the gas is introduced with a pressure just sufficient for circulating through the electrifying members; but where this pressure is not sufficient for acting upon and moving blades arranged like those of a turbine the expansive action of the gases may be sufficiently powerful for allowing a part of the mechanical energy being taken from the shaft and used, if desired, for actuating the source of electricity.

Having now fully described my invention, what I claim as new, and desire to secure by Letters Patent, is as follows:

1. An ozone fan or ventilator comprising a casing of two separable sections, each section having a side opening or inlet communicating with the interior of the casing and an outlet, a dielectric diaphragm or partition interposed between the two separable sections and dividing the casing into two chambers, a shaft-bearing on each section, a rotary shaft of insulated material, means for supporting the said shaft in the bearings, a fan or set of wings attached to said rotary shaft and in each of the chambers or separable sections insulated from each other and separated by the dielectric partition, and means for conducting a current of electricity of high voltage and frequency between the two separated and insulated fans.

2. An ozone fan or ventilator comprising a casing of two separable sections, each section having a side opening or inlet communicating with the interior of the casing and an outlet, a dielectric diaphragm or partition interposed between the two separable sections and dividing the casing into two chambers, a shaft-bearing for each section, a frame attached to each bearing, means for securing said frame to a separate section at its side opening, a rotary shaft of insulating material, means for supporting the said shaft in the bearings, a fan or set of wings attached to the rotary shaft and in each of the chambers or separable sections, the fans or sets of wings insulated from each other and separated by the dielectric partition and means for conducting a current of electricity of high voltage and frequency between the two insulated and separated fans.

3. An ozone fan or ventilator comprising a casing of two separable sections of insulating material, each section having a side opening or inlet communicating with the interior of the casing and an outlet, a dielectric diaphragm or partition interposed between the

two separable sections and dividing the casting into two chambers, a shaft-bearing for each section, a frame attached to each bearing, means for securing each frame to a separable section at its side opening, a rotary shaft of insulating material, an independent shaft or rod in each of the bearings for supporting the rotary shaft of insulating material, a fan or set of wings attached to the rotary shaft and in each of the chambers or separable sections, the fans or sets of wings insulated from each other and separated by the dielectric partition, means for independ-

ently or electrically connecting each of the fans or sets of wings with one of the independent shafts or rods in the bearings and means for conducting a current of electricity of high voltage and frequency to each of the bearings and to the two separated and insulated fans. 15

In testimony whereof I have hereunto set my hand in presence of two witnesses.

FREDERIC DE MARE.
